AUTOMATIC WILDLIFE FEEDING APPARATUS

Leslie Edward Gallup, Box 57,
Morrisville, N.C. 27560

Filed Oct. 28, 1968, Ser. No. 14,189

Term of patent 14 years

Int. Cl. D30—02

U.S. Cl. D30—13

FIGURE 1 is a perspective view of an automatic wildlife feeding apparatus embodying my new design, as seen from one side thereof;

FIGURE 2 is a perspective view of the same as viewed from the opposite side thereof;

FIGURE 3 is a side elevation thereof, viewed from the same side as FIGURE 1;

FIGURE 4 is an end elevation thereof as seen from the right of FIGURE 3; and

FIGURE 5 is an end elevation thereof, viewed from the left of FIGURE 3.

I claim:

The ornamental design for an automatic wildlife feeding apparatus, substantially as shown.
